DESIGN FOR A SHELF BRACKET

Harold Van Doren, Philadelphia, Pa., assignor to
Gerity-Adrian Manufacturing Corporation, a
corporation of Michigan

Application November 9, 1944, Serial No. 116,237

Term of patent 14 years

(Cl. D33—3)

To all whom it may concern:

Be it known that I, Harold Van Doren, a citizen
of the United States, residing at Philadelphia, in
the county Philadelphia and State of Pennsyl-
vania, have invented a new, original, and orna-
mental Design for a Shelf Bracket, of which the
following is a specification, reference being had
to the accompanying drawing, forming part
thereof.

In the drawing,

Figure I is a top plan view of a shelf bracket
showing my new design;

Figure II is a side elevational view; and

Figure III is a front elevational view.

Figure IV is a transverse sectional view taken
on the line IV—IV of Figure II.

I claim:

The ornamental design for a shelf bracket, sub-
stantially as shown.

HAROLD VAN DOREN.
